US0D1042602S

(12) **United States Design Patent** (10) **Patent No.:** **US D1,042,602 S**
(45) **Date of Patent:** **** Sep. 17, 2024**

(54) **HOLDER FOR ELECTRONIC DEVICE**

(71) Applicant: **SHENZHEN DIEPIN TECHNOLOGY CO., LTD.,**
Guangdong (CN)

(72) Inventor: **Weihao Chen**, Shenzhen (CN)

(73) Assignee: **SHENZHEN DIEPIN TECHNOLOGY CO., LTD.,** Shenzhen (CN)

(**) Term: **15 Years**

(21) Appl. No.: **29/871,306**

(22) Filed: **Feb. 16, 2023**

(30) **Foreign Application Priority Data**

Sep. 29, 2022 (CN) 202230650662.9
